UNITED STATES PATENT OFFICE.

GEORGE W. TROOP, OF NEW BRITAIN, CONNECTICUT, ASSIGNOR TO THE NORTH & JUDD MANUFACTURING COMPANY, OF NEW BRITAIN, CONNECTICUT, A CORPORATION OF CONNECTICUT.

BUCKLE.

1,323,933.

Specification of Letters Patent.

Patented Dec. 2, 1919.

Application filed August 20, 1918. Serial No. 250,650.

To all whom it may concern:

Be it known that I, GEORGE W. TROOP, a citizen of the United States, residing at New Britain, in the county of Hartford and 5 State of Connecticut, have invented certain new and useful Improvements in Buckles, of which the following is a specification.

This invention relates to buckles. A buckle involving the invention may as will be clear, 10 be employed in a variety of different ways, for instance in connection with a belt to hold the same closed. While as will be inferred the belt equipped with the buckle is primarily intended for human wear, I am 15 in no sense restricted in this particular, because it can be employed in the art of harness and in other ways. Among the primary objects of the invention is the provision of a buckle which can be easily and inexpensively 20 made and which has means of a positive and certain character for securely preventing accidental movement of the coöperating belt with respect to the buckle.

In the drawings accompanying and forming 25 part of the present specification I have shown in detail one convenient form of embodiment of the invention which to enable those skilled in the art to practise the invention will be set forth fully in the following description. I am not necessarily restricted to this particular disclosure; I may 30 depart therefrom in several respects within the scope of the invention defined by the claim following said description.

35 Referring to said drawings:

Figure 1 is a face view of a belt equipped with a buckle involving the invention.

Fig. 2 is a side elevation,

Fig. 3 a longitudinal section, and

40 Fig. 4 an inside face view of the same.

Like characters refer to like parts throughout the several views.

As will be clear the buckle may be utilized in a variety of different ways, for instance as shown in connection with a belt such as 2. Associated with this belt, band or strap 2 is a buckle such as that denoted in a general way by 3. The belt or strap may be made of any suitable material such 45 as leather, while the buckle can I find be advantageously made from sheet metal stock.

The buckle includes in its structure a body piece or section such as that denoted in a general way by 4. This body piece or section 50 in turn comprises a somewhat elong-

gated foundation portion 5 longitudinally arched, the concave surface being on the inner side and the convex on the outer side. The lateral parts of this foundation portion 5 are provided with longitudinal flanges 6 60 in parallelism with each other and integral as shown with the foundation portion 5. The said side flanges 6 in turn are provided practically centrally of their length with the inwardly extending ears or lugs 7 having perforations as 8 which provides for the flexible mounting of a clamping or tongue member such as that denoted in a general way by 9.

The clamping or tongue member may 70 within certain respects vary, although that shown and now to be described answers my requirements in a proper manner. This clamping or tongue member 9 involves a main or mounting portion as 10 which is 75 practically flat and a clamping portion 11 which is somewhat arched or bowed transversely of itself, so that in effect the active surface of the clamping or binding portion can really function as a cam. This clamping or binding portion 11 as shown is 80 mounted with the main or mounting portion 10 by a bowed connecting portion 12 from which as will be clear the said clamping or tongue member can be easily and 85 quickly made in one piece. As shown the main or mounting portion 10 has on opposite ends between its inner and outer extremes, the coincident lateral extensions or pivots 13, which although they are of rectangular shape, enter the circular openings or perforations 8 to which I have already 90 referred. The width of these lateral extensions or pivots 13 is a trifle less than the diameter of said openings or perforations, 95 so as to provide for the necessary turning movement of the clamping or tongue member 9. This clamping or tongue member can be obviously formed by doubling sheet stock on itself in such way as to secure the necessary finished article. As a matter of fact the tongue member itself can be blanked as to all its portions from sheet stock. The clamping or binding portion 11 of the tongue member is peripherally roughened as at 14, in view of which said active portion can obtain a substantial hold upon a belt or strap such as 2 in the manner I will hereinafter describe.

One end of the belt or strap is relatively 110

permanently connected with the buckle 3, the other end being capable of separable or detachable association therewith in the manner which I will hereinafter describe. I 5 will now set forth the means shown for securing the permanent connection. Connected with one end of the belt or strap 2 is a terminal as 15 which may be of sheet metal. This terminal has at its forward 10 portion the eye 16 adapted to flexibly fit around the pivot 17 at the rear of the main or mounting portion 10. In view of this circumstance it will be clear that the terminal 15 and the clamping or tongue member 15 9 can be freely moved with respect to each other.

It will be supposed that the parts, except the free end of the belt or strap are connected up as shown in the several views, 20 and that the clamping member or tongue 9 is in its releasing position. When in this position it stands practically at right angles to the foundation portion 5 of the buckle. In view of this circumstance it becomes a 25 simple matter to slip the free portion of the belt or strap along the inner surface of the foundation portion 5 between the flanges 6 thereof. When this is done the two end portions of the strap will be relatively moved oppositely and on such motion the terminal 15 will be moved relatively toward the left or outwardly, and will as a 30 consequence swing the rear part of the main

or mounting portion 10 toward the foundation portion 5, in view of which circumstance the clamping, binding or cam portion 11 will bite into the free end portion of the strap or belt and will press the same substantially against the foundation portion 5, the greater the pull the greater being the 40 pressure of the clamping portion upon the free end portion of the strap.

What I claim is:

A buckle comprising a body having a foundation piece furnished with side flanges 45 to receive between them a strap, a sheet metal member having a flat mounting portion and a transversely bowed cam portion integral with the mounting portion the bowed cam portion forming a continuation 50 of the mounting portion and its rear end being adjacent to the rear end of the mounting portion, the mounting portion being provided with lateral integral pivots and the flanges being provided with ears having 55 openings to receive the respective pivots, the cam portion being roughened and engaging between its ends, the strap between the flanges and acting to press the strap against said foundation piece.

In testimony whereof I affix my signature in the presence of two witnesses.

GEORGE W. TROOP.

Witnesses:

JOHN F. CARPMILL,
HEATH SUTHERLAND.
